UNITED STATES PATENT OFFICE.

WILLIAM LANZ, OF CHICAGO, ILLINOIS.

SHOE.

SPECIFICATION forming part of Letters Patent No. 729,361, dated May 26, 1903.

Application filed December 6, 1902. Serial No. 134,206. (No model.)

To all whom it may concern:

Be it known that I, WILLIAM LANZ, a citizen of the United States, and a resident of Chicago, county of Cook, and State of Illinois, have invented certain new and useful Improvements in Shoes, of which the following is a specification, and which are illustrated in the accompanying drawings, forming a part thereof.

10 This invention relates to an improved shield or guard designed to prevent engagement with the hooks of shoes, boots, leggings, gaiters, and other footwear, adapted to be secured by lacing with the hem, lace, fringe, 15 or open-work of skirts or other articles of apparel.

The invention has for its object to provide a shield or guard of the character referred to which does not appear as an independent 20 part of the shoe, but is preferably contained within or located entirely under the upper of the shoe, so as not to detract from the appearance of the shoe.

25 The invention also contemplates the provision of a shield or guard adapted to deflect the object or material from the sides as well as the front of the hooks, it being readily understood that the hem or open-work of a skirt is more likely to engage the lower side of the 30 hooks than the front thereof, inasmuch as the lower side is in the line of pull of the article of apparel.

35 The invention comprises generally a laced shoe having surface recesses adjacent to each of the meeting edges of its upper and lacing-hooks located within such recesses; and it consists of the parts and arrangement of parts hereinafter described, particularly designated in the claims, and illustrated in the accompanying drawings, in which—

40 Figure 1 is a perspective of a shoe, showing my improved guard or shield applied thereto. Fig. 2 is a section on the line $x-x$ of Fig. 1. Fig. 3 is a section on the line $y-y$ of Fig. 1. Fig. 4 is a detail of the pad forming the guard or shield. Fig. 5 is a portion of a shoe-upper having a modified form of the guard or shield applied thereto, and Fig. 6 is a section on the line $z-z$ of Fig. 4.

45 50 In the drawings I have shown an ordinary shoe 10, provided at the top and near the front edge of the upper thereof with the usual lac-

ing-hooks 11, designed to be engaged by lacing 12 for securing the shoe on the foot.

The shield or guard consists of a pad 13, 55 made of a yielding or elastic material, such as rubber or leather, located back of the row of hooks at each edge of the shoe-upper and adapted to deflect therefrom or over the same any object or material coming in contact with 60 or brushing against the foot or leg and preventing engagement of the same with the hooks. The pad 13 is chamfered or tapered from its edge adjacent the hooks 11 toward its rear edge and is preferably secured to 65 the inside of the shoe-upper. A pocket 14, conforming to the shape of the pad, is formed in the shoe-upper by pressing the latter outwardly, as shown, by suitable dies, and as thus arranged the shoulder 15 is provided 70 adjacent the row of hooks, which gradually tapers off into the shoe-upper, as shown in Figs. 2 and 3. Preferably the pad 13 is provided with a scalloped edge, Fig. 4, each of the outwardly-bowed or forwardly-projecting 75 rounded portions 16 extending in between adjacent pairs of the hooks 11, as shown in Fig. 1. As will be seen on referring to Figs. 2 and 3, the pad tapers on its outer face from the front edge of the bowed portions 16, which extend 80 to or substantially to the front of the hooks 11, thereby projecting from the face of the shoe-upper beyond the opening of the hooks, as indicated by the dotted line, Fig. 3. The 85 hooks being located in the recesses 17 between the bowed portions 16, it results that the sides as well as the front of the hook are guarded and engagement therewith by any object or material effectually avoided. The pad may be secured within the pocket 14, as 90 shown in the sectional views, Figs. 2, 3, and 6. As there illustrated, an inner facing 18 is provided, between which and an interposed backing 19 the pad is secured to the upper at the rear edge by stitching and at the front 95 edge by the riveted hooks 11 or in any other suitable manner. The pad 13 may have a forwardly-extending web 20, through which the fastening means pass to assist in securing the same.

100 Instead of forming the pad with a scalloped edge it may be made as shown in Figs. 5 and 6, the shoulder formed by the front edge of the tapering pad 21 being straight. Here, too,

the pad is chamfered or tapered, as shown in Fig. 6, and may be secured in place in the same manner as the scalloped guard or shield shown in Figs. 2 and 3.

5. The guard or shield may be placed a sufficient distance from the hooks to permit of the entrance of the lacing, although it would readily yield to accommodate the same. Moreover, because of the flexibility of the guard or shield, due to the fact that the pad thereof is a comparatively thin strip and secured within the shoe-upper itself, no stiffness is imparted to the shoe, which readily adapts itself to the movement of the foot of the wearer, as

15 in the case of the ordinary shoe.

It is to be understood that the present invention is adapted in its use not only to shoes or boots, but also to leggings, gaiters, and other footwear provided with hooks engaged

20 by lacings for securing the same to the wearer.

I claim as my invention—

1. In combination with a shoe having lacing-hooks, a pad secured to the shoe-upper and having a shoulder facing the hooks and

25 tapering rearwardly and inwardly from the shoulder.

2. In combination with a shoe having lacing-hooks and the upper of which is provided with a rearwardly and inwardly tapering

30 pocket on its inner face providing a shoulder at the front of the same adjacent the hooks,

a yielding pad secured in the said pocket and conforming to the contour of the same.

3. In combination with a shoe having lacing-hooks, a yielding pad secured to the inner side of the shoe-upper and provided with a scalloped shoulder the outwardly-bowing portions of which extend between adjacent pairs of the hooks.

4. In combination with a shoe having a lacing-hook and the upper of which is provided with a pocket on its inner face decreasing in depth rearwardly from the hooks, a pad located in and conforming to the contour of the pocket.

5. In combination with a shoe or the like having lacing-hooks, a guard or shield having a shoulder which bows inwardly between adjacent pairs of hooks and extends the entire length of the sides as well as at the front

45 of the hooks above the openings thereof.

6. A shoe-upper having surface recesses adjacent to the meeting edges thereof, and lacing-hooks located within such recesses.

7. A laced shoe having surface recesses in

55 its upper adjacent to and opening toward the meeting edges thereof, and hooks located within such recesses.

WILLIAM LANZ.
